FASTENER DRIVING TOOL

Edward Krantz, Chicago, Ill.; Helen Krantz, administratrix of said Edward Krantz, deceased, assignor of one-half to Valentine Pearson and one-half to Henry A. Torstenson, both of Chicago, Ill.

Application September 15, 1939, Serial No. 294,992

1 Claim. (Cl. 1—46)

One of the objects of this invention is to provide a fastener-driving tool in which the driving hammer is retracted and released by a new and improved trigger mechanism which insures dependable performance.

Another object is to provide a fastener driving tool in which the fastener while being driven is guided in its movement by a new and improved supporting device which keeps the fastener from dropping and insures the same being driven straight.

Another object is to provide an improved fastener, in the form of a specially designed tack, incorporated with a large number of similar tacks in a unified strip, for use in a tacker constructed in accordance with the invention.

While the foregoing statements are indicative in a general way of the nature of the invention, other more specific objects and advantages will be apparent to those skilled in the art upon a full understanding of the improved tool, tack and tack strip.

A preferred embodiment of the invention is presented herein for the purpose of exemplification, but it will of course be appreciated that the invention is susceptible of incorporation in other structurally modified forms coming equally within the scope of the appended claim.

In the accompanying drawings:

Fig. 1 is a side view of a tacker constructed in accordance with the invention:

Fig. 2 is a vertical longitudinal section through the tacker, taken on the line 2-2 of Fig. 3.

Fig. 3 is a bottom view of the tacker:

Fig. 4 is a fragmentary sectional view, corresponding to a portion of Fig. 2, showing the hammer just as it is starting to descend;

Fig. 5 is a horizontal transverse section through the head of the tacker, taken on the line 5-5 of Fig. 4;

Fig. 6 is a vertical transverse section, taken on the line 6-6 of Fig. 4;

Fig. 7 is a vertical transverse section through the tack strip bar, taken on the line 7—7 of Fig. 3:

Fig. 8 is a front view of one of the specially designed tacks driven by the tool:

Fig. 9 is a side view of one of the tacks; Fig. 10 is a perspective view of a section of the tack strip used with the tool; and

Fig. 11 is a top view of a section of the strip.

The tool shown in the drawings is what is known as a tacker, which is used for driving tacks, but a number of the features embodied in this tacker are equally applicable to staplers and other kinds of fastener driving tools.

The tacker is characterized by a hollow sheet metal casing 10 which comprises a vertically extending head portion 11 and a rearwardly extending hand grip portion 12. The head portion 11 is connected at its lower end to a rearwardly extending feed bar 13 which is separated from the hand grip portion 12 far enough to leave room for the fingers of the operator in grasping the portion 12.

10 The means for driving the tacks is housed within the head portion 11 of the casing and includes a block-like hammer 14 which is vertically slidable in a guideway 15 (see Fig. 5) formed between the sides 16 of the head portion, the
15 front wall 17 of the head portion and retaining strips 18 secured to the sides 16. The hammer 14 has a driving blade 19 attached to the lower portion of the front face thereof, and this blade moves vertically behind a detachable face plate
20 20 within a forwardly opening groove 21 (see Fig. 6) in the front end of the feed bar 13.

The feed bar 13 contains in its upper portion a longitudinally extending groove 22 of T-shaped cross section, in which a large number of specially designed tacks 23 of corresponding shape are held. These tacks preferably have oval shanks 24, with pointed tips 25, and laterally extending head pieces 26 of the same thickness as the shanks, and are cemented together in a unified strip 27 with the sides of the head pieces 26 and the sides of the shanks 24 in firm but readily severable contact. The groove 22 extends from one end of the bar 13 to the other and the tacks 23 are advanced toward the front end of the groove 22 by a spring strip 28 which is coiled under tension at one end on an adjustably positioned cross pin 29 and is connected at its other end to a finger piece 30. The finger piece 30 is hooked over a stud 31 on a follower 32 of T-shaped cross section which fits within the groove 22 behind the rearmost tack in the groove 22 in the feed bar by angle strips 33 (see Fig. 7) which are secured to the sides of the feed bar with their edges slightly lapping the top of the groove 22. The finger piece 30 is provided with laterally and downwardly extending wings 34 which fit about the sides of the feed bar 13 in an out-of-the-way position. When the feed bar 13 is being reloaded, the finger piece 30 is unhooked from the stud 31 on the follower 32 and temporarily hooked over a stud 35 on the rear end of the hand grip portion 12 of the casing, in an out-of-the-way position.

53 The spring strip 28 acts through the follower

32 to push the foremost tack 23 into a position directly beneath the lower edge of the raised driving blade 19, in readiness to be driven downwardly through the groove 21 every time that the blade is elevated into the position shown in Fig. 4.

The hammer 14, with the blade 19, is moved rapidly and forcibly downward by a large coil spring 36. The spring 36 fits within a socket 37 in the top of the hammer and is compressed between the bottom of the socket and the underside of a compression adjusting nut 38. The nut 38 is threaded onto a stud 39 in the top of the head portion 11 of the casing and has a knurled periphery which is exposed through openings 40 in the sides of the head portion to facilitate the making of adjustments in the amount of compression given the spring.

The hammer 14 is elevated into the striking position shown in Fig. 4 by a hand lever 41 which is pivoted at its front end to the casing on a pin 42 and extends rearwardly over the hand grip portion 12 in vertically spaced relation to the latter. The hand lever 41 is provided at its front end with a forwardly projecting finger 43 which terminates in a small sharp upwardly pointed tooth 44. This tooth is adapted to engage with a small hook 45 on the upper end of a dog 46 which is carried by the hammer 14. The dog 46 is positioned in a vertically extending groove 47 in the back of the hammer 14 and is pivotally attached to the hammer by a pin 48. The upper end of the dog 46 above the hook 45 is beveled at 49 for forwardly camming engagement with a pin 50 in the casing. When the hammer 14 is elevated into approximately the position shown in Fig. 4 by a downward movement of the hand lever 41 the upper beveled end of the dog 46 will cam against the pin 50 and be forced out of engagement with the tooth 44, thereby releasing the hammer from the hand lever and allowing the hammer to descend under the force exerted thereagainst by the then highly compressed spring 36. The hammer 14, with the driving blade 19, is shown in its lowermost position in Fig. 2, in which position the dog 46 will re-engage with the tooth 44, preferably under the action of a light spring 51 between the dog and the bottom of the groove 47, in readiness to be elevated again. The hand lever 41 is normally held in the raised position shown in Fig. 2 by a coil spring 52 which is compressed between the underside of a portion of the top of the casing and the upper side of the front end of the finger 43.

When the foremost tack 23 is being driven by the blade 19 it is supported throughout a good part of its downward movement by the front end of a small bar 53 which is located in a groove 54 in the underside of the front end of the feed bar 13. This tack-supporting bar 53 is both piv-

otally and slidably supported near its rear end on a pin 55, which pin passes through a longitudinally elongated slot 56 in the bar. The front end of the bar 53 is provided with a small vertically extending slot 57 (Fig. 3) which is just large enough to accommodate the shank 24 of the tack to be driven. When the hammer 14 is in its elevated position, in readiness for the blade 19 to drive the foremost tack, the bar 53 will be shifted forwardly by a spring 58 which engages with the rear end of the same, and will at the same time be raised into a position immediately beneath and forwardly of the front end of the tack-holding groove 22 in the feed bar 13. This upward movement of the front end of the bar 53 is brought about by a stationary cam 59 in the front portion of the groove 54 which engages with a cam surface 60 at one side of the notch formed in the bar 53. As the foremost tack descends with the blade 19 it will be supported effectively in its downward movement by the notched front end of the bar 53. Just before the tack reaches the surface into which it is to be driven the cam 59 will force the bar 53 rearwardly, causing the upper bifurcated surface of the front end of the bar 53 to withdraw rearwardly from its supporting engagement with the under sides of the laterally projecting head pieces 26 of the tack, which up to that time the bar 53 had been supporting. Upon the blade 19 being raised again in preparation for the next tack-driving operation, the front end of the supporting bar 53 will be shifted forwardly and upwardly by the spring 58 into a position where it will receive and support the next tack as the latter is driven.

I claim:

A fastener driving tool comprising a feed bar having a groove therein for the reception of a plurality of fasteners, means above the front end of the groove in the feed bar for driving the foremost fastener, and means below the front end of the groove for supporting and guiding the foremost fastener during its downward movement, said last mentioned means consisting of a bar which engages at its front end with the fastener during the downward movement of the latter, and said bar being pivotally mounted to permit its front end to move downwardly with the fastener and slidably mounted to permit its front end to move rearwardly into a position out of engagement with the fastener as the latter approaches the surface into which it is being driven, a spring for sliding the bar forwardly, and a cam in engagement with the bar at a point in front of the pivot for camming the bar rearwardly when the front end of the bar is forced downwardly by the fastener and for camming the front end of the bar upwardly when the bar is moved forwardly by the spring.

EDWARD KRANTZ.
